AUTOMATIC PHONOGRAPH

Carl G. Johnson, Chicago, Ill., assignor to J. P. Seeburg Corporation, Chicago, Ill., a corporation of Illinois

Original application January 11, 1939, Serial No. 250,311. Divided and this application April 9, 1941, Serial No. 387,748

8 Claims. (Cl. 274—10)

This invention relates to automatic phonographs and is a division from my copending application Serial No. 250,311, filed January 11, 1939.

The type of phonograph to which the present invention relates and which is fully described and illustrated in the aforesaid application, is that in which a plurality of records are retained above a turntable by means of one or more escapement mechanisms. The escapement mechanisms are actuated during the record changing cycle so as to drop the lowermost record which then falls down upon the turntable where it is played.

The escapement mechanism normally comprises two essential members, a lower supporting arm and a blade which is located thereabove approximately the thickness of one record. The arm and blade are connected together for simultaneous movement and during the actuation of the escapement mechanism, the upper blade enters the stack of records above the lowermost record and thereafter the lower supporting arm moves clear of the lowermost record so that that record alone is released. The return of the escapement mechanism to initial position returns the supporting arm to a position below the stack of records and thereafter the upper blade is withdrawn so that the next record now rests upon the lower supporting member and the upper blade is adapted to enter the stack immediately above that lowermost record on the next actuation of the escapement mechanism.

Considerable difficulty has arisen in connection with escapement mechanisms of this type in which it is attempted to intermix records of different sizes, for example ten and twelve inch records. When the lowermost record of the stack is a ten-inch record and the record immediately above it is a twelve-inch record, then the upper blade has difficulty in functioning properly. In some cases the twelve-inch record is warped so that the portion which projects beyond the ten-inch record may actually project down below the upper surface of the lowermost ten-inch record. Some records are warped so as to have an incipient umbrella formation and such records have caused considerable trouble, deforming and jamming the escapement mechanism and sometimes fracturing the records.

The principal object of the present invention is to provide means whereby a record of larger size in the second position from the bottom of the stack is elevated away from a smaller lowermost record so as to permit the upper blade to enter the stack clear of the larger record.

A further object of the invention is to provide an elevating mechanism of this type which is rendered inoperative by a record of larger size in the lowermost position.

Other objects, advantages and capabilities of the invention will appear from the following description of a preferred embodiment thereof taken in conjunction with the accompanying drawing in which:

Figure 1 is a fragmentary plan view of my improved escapement mechanism in position where the upper blade is about to clear a record of smaller size and allow the same to drop onto the lower arm;

Figure 2 is a similar view showing the upper blade about to enter below a larger record supported by a record of smaller size which rests on the lower arm;

Figure 3 is a fragmentary sectional detail view taken on the line 3—3 of Figure 2, the record elevating means being shown in normal position;

Figure 4 is a fragmentary sectional detail similar to Figure 3 showing the record elevating mechanism in position corresponding to that shown in Figure 2;

Figure 5 is a similar view showing the record elevating means in inoperative position with a record of larger size resting upon the lower arm; and

Figure 6 is a fragmentary detail view showing the manner in which the elevating mechanism is actuated by a record of smaller size.

Referring to the drawing, Figures 1 and 2 show a complete escapement mechanism comprising a lower support 10, an upper blade 11 spaced above the support 10 by a distance approximately equal to the thickness of a record. The arm 10 and the blade 11 are mounted on a vertical sleeve 12 so that they can be rotated or oscillated together about the axis of the sleeve 12.

The upper blade 11 is shown associated with a follower member 13, the function and operation of which is described in the parent application. The follower 13 is pivotally mounted on the sleeve 12 and is normally held away from the records by means of a spring 14.

It will be understood that the escapement mechanism is located to one side of a turntable 15. Thus, two or more of the escapement mechanisms may be located around the turntable to support a stack of records mounted above and in alignment with the turntable 15.

As fully described in the parent application, the turntable 15 has an elongated spindle which

projects upwardly beyond the arm 10 and blade 11 so that it passes through the central openings of a stack of records normally supported on the support 10.

Means (not shown) are provided for periodically oscillating the sleeve 12 to effect the deposition of a record from the stack supported on the escapement mechanisms onto the record. It may here be noted that the arm 10 lies normally in position indicated at 10' in Figures 2 and 6 and in this position the blade 11 and follower 13 are clear of the records which are supported exclusively upon the arms 10.

When the sleeve 12 is swung in the clockwise direction as viewed in Figure 1, the blade 11, being approximately one record thickness above the arm 10, comes into contact with the stack of records at a position above the lowermost record and it enters into the stack above the lowermost record. In Figure 1 I have shown the blade 11 on the point of entering the stack above a ten-inch record while in Figure 2 I have shown it entering the stack above a twelve-inch record.

It will readily be understood that continued clockwise movement of the sleeve 12 brings the arm 10 clear of the lowermost record so that this record is free to fall downwardly upon the turntable, being guided by the elongated spindle which passes through its central opening. The movement of the sleeve 12 is now reversed so that the arm 10 is brought beneath the stack of records and in spaced relation thereto owing to the absence of the previous lowermost record. This reverse or return movement of the sleeve 12 brings the blade 11 clear of the lowermost record so that the stack of records is then free to fall the thickness of one record until it rests upon the arms 10 in the position 10'.

It may here be noted that the return movement of the blade 11 brings it into engagement with the follower 13, this engagement being frictional as described in the parent application. When the blade 11 moves into contact with the stack of records and is about to enter above the lowermost record, the follower 13 is arrested by engagement with the lowermost record as shown in Figures 1 and 2, and the blade 11 moves into the stack and clears the follower 13. When this occurs, the spring 14 returns the follower 13 to its initial position which is defined by an abutment 19 which engages stops in a standard 20 in which the sleeve 12 is mounted.

The element 16, as is fully explained in the parent application, controls the disposition of the player arm, depending upon the size of the record, this mechanism being either manually controlled or automatically controlled by the member 16'. The follower 13 carries a projecting end 17 which is adapted to engage a member 18 to terminate the operation of the phonograph when the follower 13 does not engage a record of either of the two sizes for which the phonograph is intended.

The present invention is primarily concerned with means which will now be described for effecting the elevation of a record of larger size in the second lowermost position from a record of smaller size in the lowermost position. It will, of course, be understood that any records above the second lowermost are at the same time elevated.

If the lowermost record on the stack is a ten-inch record and the record immediately thereabove is a twelve-inch record, difficulties may be experienced if the marginal portions of the

twelve-inch record are warped downwardly into the path of the blade 11. To prevent these difficulties, I prefer to provide each arm 10 with elevating means which are inoperative when the lowermost record is a twelve-inch record and which are rendered operative when the lowermost record is a ten-inch record, so as to elevate somewhat the second record from the bottom, if that record is a twelve-inch record.

For this purpose, each arm 10 is preferably provided with a longitudinal slot 21. Adjacent the outer end of the arm 10, that arm is provided with an inferior recess 22 which communicates with the slot 21. Within the innermost end of each slot 21, is pivotally mounted an elevating member 23 which is somewhat elongated and is pivoted near one end within the slot so that it can be swung upwardly, as shown in Figure 4, to project above the arm 10 a distance somewhat more than the thickness of a record. It will readily be understood, with reference to Figure 4, that the blade 11 can move freely in between the space between the two records shown in this figure when the second lowermost record is elevated in this manner.

The member 23 may suitably be of oval form. An actuating member 24, suitably of T-shape, is pivotally connected to the elevating member 23 to effect its swinging movement. The actuating member is normally biased outwardly and upwardly, as shown in Figure 3, by means of a spring 25 which is connected to the arm 10 at its outer end and to a downwardly projecting arm 26 of the actuating member 24. When thus biased, the arm 27 of the actuating member 24 projects upwardly above the surface of the arm 10 and is located at the outer end of the slot 21 shown in Figure 3. The upward projection of the arm 27 is limited by a pin 28 mounted on the actuating member 24. This pin extends on each side beyond the slot 21 and engages the under side of the arm 10 within the recess 22.

When a record has been dropped onto the turntable and the arms 10 and 11 are moving in the counterclockwise direction, as viewed in Figures 1 and 2, so as to drop the remaining stack of records onto the arms 10, then the lowermost record of the stack supported on the arms 11, drops downwardly beyond the upwardly projecting arm 27, as will be best seen in Figures 1 and 2. Consequently, the arm 27 is moved into its inoperative position, shown in Figure 5. If the lowermost record is a twelve-inch record, the arm 27 remains in its depressed position when the arm 10 reaches its final position which is shown at 10' in Figure 2. If, however, the lowermost record is a ten-inch record, the arm 27 clears it in the final position 10' of the arm 10 (Figure 6) so that the arm 27 moves upwardly into the position shown in Figure 3.

During the next record-changing cycle, the arm 27 engages the periphery of the lowermost ten-inch record and the member 24 is displaced from its position shown in Figure 3 to its position shown in Figure 4. As a result, the elevating members 23 are moved out into elevating position.

In the event that the next superior record is a twelve-inch record, it is engaged by the elevating members 23 and said next superior record and the records resting upon it are elevated in the manner shown in Figure 4.

It is to be noted from Figure 2, that the arm 11 moving inwardly in the clockwise direction, becomes located below the marginal portion of the twelve-inch record while the same is still

elevated by the engagement of the arm 27 with the lowermost ten-inch record. Consequently, even if the twelve-inch record is badly warped, it will be clear of the arms 16.

Although the invention has been described in connection with specific details of a preferred embodiment thereof, it must be understood that such details are not intended to be limitative of the invention except in so far as set forth in the accompanying claims.

Having thus described my invention, what I claim as new and desire to secure by Letters Patent of the United States is:

1. An escapement mechanism for automatic phonographs comprising an upper and a lower supporting member connected together for simultaneous movement, said members being spaced vertically and in the direction of movement to serve as an escapement for dropping the lowermost record of a stack of records resting thereon, abutment means on the lower member adapted to engage the periphery of a record of lesser size during the record-dropping cycle, and elevating means located beyond said record and controlled by said abutment means whereby a record of larger size immediately above the lowermost record may be elevated from the lowermost record.

2. An escapement mechanism for automatic phonographs comprising an upper and a lower supporting member connected together for simultaneous movement, said members being spaced vertically and in the direction of movement to serve as an escapement for dropping the lowermost record of a stack of records resting thereon, said lowermost record having a longitudinal slot and an inferior recess communicating with said slot, an actuating member in said recess having an upwardly directed arm adapted to be projected through the slot above the surface of said lowermost member, a spring biasing said actuating member to its outermost and uppermost position, means on said actuating member preventing an excessive upward movement of said arm, an elevating member pivotally mounted in said slot and normally below the upper surface of said lower member, and means connecting said actuating member and said elevating member whereby the latter is swung upwardly when the actuating member is moved inwardly, said slot being located so that the upwardly directed arm of the actuating member engages the periphery of a record of lesser size during the record-changing cycle and effects the movement of the elevating member to elevating position, said elevating member being arranged to engage the marginal portion of a record of larger size.

3. In an escapement mechanism for automatic phonographs comprising a lower supporting member adapted to support a stack of records thereabove and an upper supporting member connected to said lower supporting member for simultaneous movement therewith, the upper member being adapted to enter said stack of records above the lowermost record whereby said lowermost record is released from the stack, in combination, elevating means for elevating larger records only in the next to lowermost position in the stack, and actuating means associated with said supporting members for actuating said elevating means, said actuating means being arranged to be brought into actuating engagement with said stack during the record-discharging movement of said members to effect elevation of

a record of larger size in the next to lowermost position.

4. In an escapement mechanism for automatic phonographs comprising a lower supporting member adapted to support a stack of records thereabove and an upper supporting member connected to said lower supporting member for simultaneous movement therewith, the upper member being adapted to enter said stack of records above the lowermost record whereby said lowermost record is released from the stack, in combination, elevating means for elevating larger records only in the next to lowermost position in the stack, and actuating means associated with said supporting means for actuating said elevating means, said actuating means being arranged to be brought into actuating engagement with said stack during the record-discharging movement of said members to effect elevation of a record of larger size in the next to lowermost position, said actuating means being arranged to be rendered inoperative by a record of larger size in the lowermost position in the stack.

5. In an escapement mechanism for automatic phonographs comprising a lower supporting member adapted to support a stack of records thereabove and an upper supporting member connected to said lower supporting member for simultaneous movement therewith, the upper member being adapted to enter said stack of records above the lowermost record whereby said lowermost record is released from the stack, in combination, elevating means for elevating larger records only in the next to lowermost position in the stack, and actuating means associated with said supporting member for actuating said elevating means, said actuating means being arranged to be brought into engagement with a record of smaller size in the lowermost position of the stack during the record-discharging movement of said members to be actuated by said engagement to effect elevation of a record of larger size in the next to lowermost position.

6. In an escapement mechanism for automatic phonographs comprising a lower supporting member adapted to support a stack of records thereabove and an upper supporting member connected to said lower supporting member for simultaneous movement therewith, the upper member being adapted to enter said stack of records above the lowermost record whereby said lowermost record is released from the stack, in combination, elevating means for elevating larger records only in the next to lowermost position in the stack, and actuating means associated with said supporting member for actuating said elevating means, said actuating means being arranged to be brought into engagement with a record of smaller size in the lowermost position of the stack during the record-discharging movement of said members to be actuated by said engagement to effect elevation of a record of larger size in the next to lowermost position, said actuating means being arranged to be rendered inoperative by a record of larger size in the lowermost position.

7. In an escapement mechanism for automatic phonographs comprising a lower supporting member adapted to support a stack of records thereabove and an upper supporting member connected to said lower supporting member for simultaneous movement therewith, the upper member being adapted to enter said stack of records above the lowermost record whereby said

lowermost record is released from the stack, in combination, elevating means for elevating larger records only in the next to lowermost position in the stack, and actuating means therefor, said elevating and actuating means being carried by and movable with said supporting members, said actuating member being arranged to engage the periphery of the lowermost record of a smaller size to effect operation of said elevating means.

8. In an escapement mechanism for automatic phonographs comprising a lower supporting member adapted to support a stack of records thereabove and an upper supporting member connected to said lower supporting member for simultaneous movement therewith, the upper member being adapted to enter said stack of

records above the lowermost record whereby said lowermost record is released from the stack, in combination, elevating means for elevating larger records only in the next to lowermost position in the stack, and actuating means therefor, said elevating and actuating means being carried by and movable with said supporting members, said actuating member being arranged to engage the periphery of the lowermost record of a smaller size to effect operation of said elevating means, said actuating means being normally located below records of larger size and beyond records of smaller size, said actuating means being arranged to be depressed and rendered inoperative by a record of larger size in the lowermost position.

CARL G. JOHNSON.
